METHOD OF AND MACHINE FOR
REFORMING LASTS

Jeremiah Fitzpatrick, East Weymouth, Mass.

Application July 7, 1934, Serial No. 734,126

17 Claims. (Cl. 144—309)

This application is a continuation in part of my application Serial No. 682,264 filed July 26, 1933, Method of reforming lasts, which has matured into Patent No. 1,969,739 Aug. 14, 1934.

5 The present invention relates to a method of and machine for reforming old lasts, or lasts that have been used, in conformity with a new or different model.

In reforming old lasts it is important to so 10 support each last to be reformed during the last turning operation that it will rotate about an axis that corresponds accurately with the axis about which the model last is turned.

The method of reforming lasts described and 15 claimed in the above mentioned application works entirely satisfactory so long as the last has not been sprung or bent axially, but it sometimes happens that a hinged last which is to be reformed has become bent or sprung at the hinge, 20 and if these lasts are lined up by engaging the rounded toe and heel thereof as contemplated by the method of said application the hinge portion of the last will lie more or less off centre.

In order to overcome this difficulty the present 25 invention is directed to a method of and apparatus for working entirely from the heel part of the last while lining up the same preparatory to remodeling the last on an axis corresponding to the axis of the model last.

30 The present method may be used in reforming either one-piece or hinge lasts, and to reform lasts in which the old fore part presents sufficient wood for the turning operation or has been built up for this purpose, or in which the entire 35 or major portion of the fore part of the last is replaced with a new fore block.

One important feature of the invention resides 40 in the method of and apparatus for accurately supporting the heel part of a last with the axis upon which it is to be reformed in a definite predetermined position, and while thus supported forming longitudinal and transverse borings therein which bear a predetermined relation to said axis and which borings will serve to accurately position the last while a centre bore is formed in the toe thereof.

Another feature of the invention resides in adjustable stops adapted to engage the opposite side 50 of a last and in means for moving these stops simultaneously towards each other to centre the last in one longitudinal plane.

A further feature resides in means for supporting the heel engaging V-block and adjacent seat for the tread of the heel for adjustment 55 along an inclined path so that this adjustment

will accommodate the increased length of the larger lasts and at the same time the increased depth of these lasts from the central axis to the tread of the heel.

Other features of the invention and novel combination of parts in addition to the above will be hereinafter described in connection with the accompanying drawings which illustrate good practical forms thereof.

In the drawings:

Fig. 1 is a side elevation of a lining up and boring machine designed for carrying out the present invention.

Fig. 2 is a vertical sectional view taken on the line 2—2 of Fig. 1.

Fig. 3 is a top plan view of Fig. 1.

Fig. 4 is a cross section of a detail of the mechanism shown in Fig. 3.

Fig. 5 on an enlarged scale is a longitudinal sectional view through the heel supporting mech- 20 anism of Fig. 1.

Fig. 6 is a side view of the last supporting mechanism of Fig. 1.

Fig. 7 is a top plan view of Fig. 6.

Fig. 8 is a longitudinal sectional view of the 25 slideway for the last engaging side stops.

Fig. 9 is a side elevation of a model last.

Fig. 10 is a rear end view of a device for supporting a last while a turning centre is formed in the toe thereof.

Fig. 11 is a perspective view of the device of Fig. 10 showing a turning centre being formed in the toe of a last to be reformed.

Fig. 12 is a side elevation of a modification and shows a lathe chuck having heel engaging 35 means constructed in accordance with the present invention for supporting a last to be reformed on a predetermined axis.

Fig. 13 is a front view of the chuck mechanism of Fig. 12; and

Fig. 14 is a bottom plan view of this chuck mechanism.

The important thing in reforming lasts in accordance with the present invention, as above pointed out, is to provide like axes for the model 45 last and lasts to be reformed. If the lasts are provided with like axes then similar points on the model last and reformed lasts will lie the same distance from the axes of rotation. If, however, these axes are not similarly located in the model 50 last and last to be reformed, then similar points on the two lasts will lie different distances from the respective axes, with the result that when the last to be reformed is acted upon by a cutter under the control of the model last, portions 55

of the wood which should remain on the last being reformed may be cut away while other portions of the last may be under size.

In turning new lasts the accurate location of the axis of rotation is not necessarily important because if the last block is sufficiently large to provide plenty of wood at all sides of the axis of rotation then the cutter controlled by the model last will cut the block of wood to the desired size and shape, but if there is not plenty of wood at all portions of the last or last block then the accurate location of the axis becomes important.

In locating the last's axis of rotation in accordance with the present invention the more reliable portions of the old last are selected to work from. The metal heel plate and rounded end of the heel are therefore used in locating the position of the axis of rotation in the heel; and the longitudinal, central, vertical plane of the heel is located by placing the rounded heel in a V-block, while the distance the axis is to be located up from the heel plate is determined by measuring up from the heel plate about $1\frac{1}{4}$ inches for a size seven men's last, as this is found by measuring a large number of lasts to come very close to the original axis of rotation.

The axis of rotation for the model last is accurately located in the toe thereof by placing the toe of the last in a V-block to find the longitudinal, central, vertical plane of the toe, and the axis is located in this plane preferably at the point where the tread and last upper meet.

After the model last has been properly centered and has been provided with borings to support it upon the last turning lathe, this last is used, in accordance with the present invention, to facilitate the adjustment of a jig or last supporting mechanism so that each last of the series of lasts to be reformed may be easily and accurately supported from its heel portion alone to receive borings that bear a definite predetermined relation to the axis upon which the last is to be reformed. In this manner each last to be reformed is provided with an axis of rotation which accurately corresponds to the axis of rotation of the model last.

The mechanism illustrated for carrying out the objects of the present invention will now be described. The machine shown in Fig. 1 for lining up and drilling the lasts is for the most part similar in construction and operation to the machine shown in Fig. 1 of my application above mentioned. The principal difference between the two machines resides in the fact that in the earlier machine it is intended to use the toe and heel receiving V-blocks to line up the model last and also the old lasts to be reformed, whereas in the present machine it is intended to use both the toe and heel receiving V-blocks to line up only the model last, as the other lasts are lined up and supported in this machine entirely from the heel part of the last.

The machine of Fig. 1 is provided with a bed plate 10 supported at the desired height from the floor by legs 11 and the upper face of the bed plate 10 is provided with the longitudinally extending ribs or guideways 12. Mounted upon the bed plate near the central portion thereof is a jig or last supporting device 13 and this jig is slidably mounted upon the guideways 12 for movement longitudinally of the bed plate relative to a side drill to be described, and means are provided for clamping the jig in its adjusted position along the bed plate. The jig 13 is adapted to support a last L with its tread up as shown while

the last positioning bores are being formed therein.

The jig 13 is shown as provided with the uprights 14 and these uprights not only support the heel engaging V-block 15 as in the earlier application but may also support adjustable pins that engage the tread of the heel portion of the last, and side stops that engage the opposite sides of the heel portion of the last.

Adjacent the forward end of the jig 13 is slidably mounted a slide 16 to which is rigidly secured the toe engaging V-block 17 and this slide 16 is moved towards and from the heel receiving V-block 15 by means of the threaded shaft 18 that is rigidly or non-rotatably secured to the base portion 19 of the slide 16. The shaft 18 is provided with a threaded sleeve or nut rotatably mounted within the housing 20 at one end of the jig and this sleeve is rotated to adjust the shaft by a gear 21 which is rotated by the crank handle 22.

The heel receiving V-block 15 is formed in the construction shown by securing two inclined blocks 15 to the under face of a supporting plate or slide 23 and the lower face of this slide forms an abutment against which the metal heel plate of a last may rest when the last is placed in the jig with its heel plate up as shown in Fig. 1. Mechanism is provided, which will later be described, for raising and lowering the slide 23 and for moving it longitudinally of the jig to accommodate different size lasts.

The last is firmly held against the abutment of slide 23 in the construction shown by a foot operated plunger 24 at the upper end of which is provided a pivoted head 25 that engages the heel portion of the last as shown. This plunger is urged upwardly by pressing upon the foot treadle 26 pivoted at 27 and connected by a link 28 to an end of the operating lever 29. This lever is pivoted intermediate its ends at 30 to the machine frame and the opposite end of the lever 29 is connected by a link 31 to the plunger 24.

The mechanism so far described may be employed to support a model last L in accurate position to receive the borings which will determine the centres about which this last will be rotated in the last turning lathe. To accomplish this the last L is positioned in the jig 13 in its inverted position as shown in Fig. 1 with its heel in engagement with the V-block 15 and abutment of the slide 23. The toe engaging V-block 17 is then moved into engagement with the toe of the last by operating the handle 22. These V-blocks engaging the heel and toe of the model last L will centre the last in the longitudinal vertical plane, and the abutment slide 23 when properly adjusted in a vertical position will bring the axis of the heel portion of the last in the proper horizontal plane. The toe portion of the last is readily set in the proper horizontal plane by moving the toe up or down until the line of intersection formed by the tread and last upper lies opposite the point of the toe boring drill 32 as shown in Fig. 1.

While the last L is thus supported the toe thereof is bored by the drill 32 to provide the last with the centre bore a (see Fig. 9). The drill 32 extends through a guiding bushing 33 in the slide 17 and the drill is secured to the driving shaft 34 journaled in a supporting bracket 35 and driven by the electric motor 36. The bracket 35 and motor 36 are mounted on a sliding base plate 37 supported by the bed plate 10 of the machine for movement longitudinally of the bed plate, and sliding movement is imparted to the plate 37 to

move the drill towards and from the work by turning the wheel having the hand levers 38.

The heel end of the last is preferably provided with three drill holes or borings *b* spaced about 5 and at equal distances from the central axis of the heel as best shown in Fig. 10, to support and drive the last in the lathe turning operation. These three bores are formed by the drills 39 which are driven by gears or the like within the 10 chuck 40 and the drills are guided by bushings 41 supported by the bracket 42. The chuck 40 is supported by a bracket 43 and the drill operating mechanism within the chuck is driven by the motor 44. The motor 44 and brackets 43 and 42 are 15 mounted upon the base plate 45 which is slidably supported by the bed plate 10 and movement of the drills 39 towards and from the work is effected by the operating wheel having the hand levers 46.

20 Means is further provided, in accordance with the present invention, for forming a transverse bore *c* in a side of the heel part of the last. This bore *c* when provided in the model last L serves to help support the last in the lathe, but the 25 transverse bore *c* when provided in the lasts to be reformed is used to help support the last during the toe centering operation as will be more fully described.

The transverse bore *c* preferably but not necessarily lies in the horizontal plane of the axis of rotation and is formed by a drill 47 mounted in a shaft 48 that is journaled in a bearing 49. The shaft is driven by the motor 50 and the motor and bearing 49 are secured to a base plate 51 that is 30 slidably supported by the portion 52 of the machine bed. The drill 47 is moved towards and from the work by operating the wheel having the handles 53.

Having described the construction for supporting and boring a model last to define its axis of rotation, the construction and operation contemplated by the present invention for providing each last to be reformed with an axis like that of the model last will now be described.

45 The method of supporting the lasts to be reformed during the boring operation is different from that of the model lasts, since the lasts to be reformed are supported entirely from the heel part upon an axis that corresponds to the axis 50 of the model last, and important means to this end resides in the side stops 54 adapted to engage and press upon the opposite sides of the heel part of the last and co-operate with the V-block 15 to centre the last in a vertical plane. 55 The heel part of the last is centered in a horizontal plane by the proper adjustment of the abutment slide 23 against which the rear end portion of the heel plate rests, and the proper adjustment of the lining up pins 55 which engage the 60 tread of the heel near the hinge portion thereof.

The side stops 54 and pins 55 are adjustably supported in the construction shown by the slide 23, and this slide is supported for adjustment along an inclined plane so that as the slide 23 is 65 moved rearwardly to accommodate larger lasts it will also move upwardly to accommodate the increased distance from the heel plate to the axis about which the last is to be reformed. The uprights 14 therefore have rigidly secured thereto 70 the inclined head 56 the inner portion of which is partly cut away to receive the slide 23, and this head, as will be apparent from Fig. 4, is provided with guideways 57 adapted to receive the ribs 58 upon the slide 23 to support the latter for sliding 75 adjustment within the head.

The slide 23 is adjusted within the head 56 by a threaded shaft 59 which turns in a nut 60 rigidly secured to the upper end of the head. This shaft is provided near its lower end with a collar 61 which is rigidly secured to the shaft by a pin 5 62, and the collar is rotatably mounted in a recess formed in the slide 23. The shaft 59 is rotated by its handle 63 and as it turns in the nut 60 the travel of this shaft will be imparted to the slide 23 by the collar 61. Accidental rotation of the 10 handle 63 is prevented by providing upon the slide 23 the extension bar 64 having at its outer end a spring plunger 65 adapted to enter a recess in the ball end of the handle lever and hold it 15 from turning.

In the construction shown the side stops 54 and leveling pins 55 are supported by the slide 23, and to this end the slide is provided with a pair of parallel guide rails 66 which extend frontwardly alongside the heel part of the last. These 20 rails serve to support a block 67 mounted therebetween for sliding movement along the rails. The block 67 is provided with a transversely extending strip 68 overlying the rails 66 and with a transversely extending strip 69 of dove-tail construction in cross section and lying under the rails 66. The arrangement is such that the block 67 is supported between the rails by the strips 68 and 69 which engage the upper and lower faces of the rails to permit longitudinal sliding 30 movement between the block and rails.

The dove-tailed strip 69 forms a slideway for the transverse slide 70 which carries the side stops 54, and rigidly secured to the rear face of the slide 70 is the upstanding block 71 which 35 extends upwardly between the rails 66 and has the overhanging portion 72 which bears upon the upper face of the strip 68. The arrangement is such that the block 67 and strips 68 and 69 secured thereto will not slide transversely of the 40 rails 66, but these parts support the transverse slide 70 and parts 71 and 72 secured thereto for transverse sliding movement to accommodate either right or left lasts. After the slide 70 has been shifted in the direction of its length the 45 desired amount it may be clamped in this position by tightening the locking screw 73. This screw extends through an elongated slot in the part 71 and has threaded engagement with the 50 underlying strip 68.

The leveling up pins 55 are slidably mounted in drill holes formed in the upright block 71 and as a result when the parts 70, 71 and 72 are shifted laterally of the rails 66 to accommodate a right or left last, the pins 55 will also be shifted 55 to accommodate the tread of the right or left last. These pins may be simultaneously adjusted either up or down by providing a fixed threaded post 74 between them extending up from the block 71 and providing upon this post a nut 75 60 having the annular slot adapted to receive the heads 76 of the pins 55 so that rotation of this nut to cause it to travel along the post 74 will 65 impart a sliding movement to the pins 55.

Since the side stops 54 and pins 55 are supported by the rails 66 of the slide 23 any movement of the slide along its supporting head will tend to impart a similar longitudinal movement to these stops and pins, but it is desirable that these stops and pins shall remain in the same 70 position longitudinal of the jig 13 for all size lasts. This is accomplished by providing between the spaced rails 66 the threaded shaft 77 which co-operates with a nut 78 non-rotatably secured in the block 67. The shaft 77 is operatively con- 75

nected to the lower end of the shaft 59 by a knuckle joint 79. The arrangement is such that rotation of the screw shaft 59 to move the slide 23 will rotate the shaft 77 to advance the block 67 forwardly an amount equal to the rearward movement of the slide. The net result of these movements is that the block 67 will remain in practically a fixed position, and the side stops 54 will remain in a position to engage all size lasts just back of the hinge line.

While the mechanism just described prevents the stops 54 from moving rearwardly with the slide 23, the elevation of the slide 23 by its movement along an inclined plane will be imparted to the block 67 and parts carried thereby. This is desirable because adjustment of the slide 23 rearwardly to accommodate a larger size last will serve to elevate the abutment upon the slide 23 for the rear portion of the heel and the leveling up pins 55 which engage the tread of the heel near the hinge.

The result of mounting all of the heel positioning mechanism on the slide 23 is that after the side stops 54 and leveling pins 55 have once been adjusted by placing a model last L in the jig in its drilling position, as above described, and the stops 54 and pins 55 have been adjusted against the model last, then the jig may be easily and quickly adjusted to accommodate either larger or smaller lasts than the model last. These different size lasts are easily provided for by simply adjusting the slide 23 along its inclined path to the desired reading of the scale 80.

For example, if the model last used in setting the jig is a size seven and it is desired to adjust the jig to receive a size ten last it is merely necessary to turn the handle 63 to adjust the slide 23 along the scale 80 to the graduation marked "10".

40 The present invention also contemplates simple means for determining the proper adjustment of the stop supporting slide 70 laterally to accommodate either a right or left last. Let it be assumed that the model last L is a "right" last, then in setting the stops 54 in engagement with the opposite sides of this model last the locking screw 73 will be released to permit the slide 70 to move laterally and the stops 54 will be moved against the opposite sides of the last. This is done by 45 rotating the right and left hand screw 81 which is journaled in a recessed portion of the slide 70 as best shown in Fig. 8. The stops are secured to threaded blocks 82 which slide in the recessed portion 83 of the slide and are advanced along the 50 slide by turning the screw 81 by means of its head 84. After the stops 54 have been moved against the sides of the last L then the locking screw 73 is tightened to lock the slide in this position, and it is retained in this position for all sizes of the 55 set of "right" lasts to be reformed, after which the slide 70 is shifted off centre to the same amount in the opposite direction to accommodate the set of "left" lasts to be reformed.

In order to simplify the operation of adjusting 60 the slide 70 an equal amount to either the right or left, the block 67 may have secured thereto the off centre stop rod 85, the inner end of which is pivoted at 86 to a plate 87 secured to the block 67. To the outer end of the rod 85 is pivotally secured the head 88 having at its lower end the 65 adjustable stop screw 89. The arrangement is such that after the slide 70 has been adjusted and clamped in its adjusted position by the screw 73 the off centre stop rod 85 is swung to one side 70 of its pivot 86 so that the stop screw 89 may be

screwed into engagement with an end of the slide 70. This defines the off centre adjustment of the slide, say to the right and a corresponding off centre adjustment to the left is secured by swinging the rod 85 to the opposite side of its pivot so that its stop screw 89 is positioned to limit the off centre adjustment of the slide 70 to the left, whereupon the slide is clamped in this new position by the screw 73.

After the last boring jig has had its slide 23, 10 stops 54 and pins 55 properly adjusted from a model last L as above described, the work of drilling the set of lasts R to be reformed so as to provide each of these lasts with an axis like that of the model last may be performed, and to accomplish this the toe receiving V-block 17 is provided with a flat plate or block 90 which will serve to press upon the toe end of a last R to be reformed without preventing the lateral movement of the toe relative to the block as the side stops 54 are 15 forced against the opposite sides of this last by turning the screw head 84.

As soon as the last R is properly positioned in the jig 13 the drills 39 and 47 are operated to form the bores b and c, the depth of each of these 20 bores being limited by suitable stops for the drills. These bores are positioned in an accurate predetermined relation to the axes about which the last R is to be reformed and serve to support the last entirely from its heel part while the turning 25 centre is formed in the toe or fore part of the last. The drill 32 is not used to bore the lasts R that are to be reformed.

The last R to be reformed may have the toe part thereof built up or the entire fore part of 30 the old last may be replaced with a new fore block B as shown in Fig. 11, and as is fully disclosed in my application above mentioned. After the last R has been provided with the bores b and c it is transferred to the machine of Fig. 11 where 35 it is supported by the bores b and c while a centre bore is formed in the new toe part of the last.

This centre boring device of Fig. 11 is for the most part similar in construction and operation 40 to the testing and centre boring device of my application above mentioned, and comprises a base or bed plate 91 having the upstanding end walls 92 and 93. In the wall 93 is journaled a drilling shaft 94 having a drill or centre forming 45 cutter 95. The shaft 94 is driven by a pulley 96 and belt 97 and the shaft is slidably mounted in its bearing and pulley and has a key driving connection with the pulley so that the shaft may be moved towards the work by engaging the handle 50 98 and sliding the shaft in its bearing.

The wall 92 is provided with the three last positioning pins 99 adapted to enter the bores b in the heel of the last R to accurately position the heel of the last. The last is further positioned in the 60 device of Fig. 11 by a pin 100 which is slidably mounted in a drill hole formed in an upright 101. This upright is secured to a carriage or slide 102 adapted to be adjusted lengthwise of the base plate 91 and clamped in the desired position of 65 adjustment by tightening the thumb nut 103.

The pin 100 is forced into the bore c until it strikes against the bottom of this hole and is then positioned so that a notch 104 in the pin receives the pivoted locking key 105 when this key is 70 swung downwardly into the notch 104. This causes the inner end of the pin 100 to lie a predetermined distance from the upright 101 so that when the pin is thus positioned and abuts against the bottom of the bore c, the last R will be cen- 75

tered both vertically and horizontally to receive the centre bore in its toe formed by the cutter 95. It is important that when the pin is locked in place by the key 105 that the inner end of this pin 5 rests firmly against the bottom of the bore c which bore is accurately drilled to the desired depth. In the present construction a spring operated plunger 106 is provided to strike against the far side of the last and force it against the pin 100. The plunger 106 is slidably supported by the upright 107 and may be provided with a pivoted last engaging head 108, and a cable 109 extending to a foot treadle, not shown, serves to retract the plunger so that when released it will 10 be forced frontwardly by the spring 110. The pin 100 has the operating handle 111.

In this manner each last to be reformed is supported entirely from the heel part while it is being provided at its heel and toe with bores which 20 define an axis that corresponds accurately with the axis of the model last.

After a last to be reformed is provided with the borings b in the heel thereof and the centre receiving bore in the toe thereof as above described, which bores are positioned to support the last to be reformed upon a like axis to that defined in the model last by the borings b and a, then the model last and last to be reformed are ready to be placed upon a last turning lathe such 30 as disclosed in Fig. 17 of the above mentioned application so that the last to be reformed will be acted upon by a cutter under the control of the model last.

In the modification shown in Figs. 12, 13 and 35 14, the mechanism of the present invention for supporting a last to be reformed from its heel part so that its axis corresponds to that of the model last, is associated with the head 112 of a last turning lathe having the spindle 113. To 40 the face of this head 112 at its central axis is secured a heel receiving V-block 114 adapted to receive the rounded heel of the last, and the heel plate of this last rests upon an adjustable abutment or plate 115 having the portion 116 that fits 45 slidably in a slotted portion 117 of the head. The plate 115 is adjusted along the head 112 by operating the adjusting screw 118 having the head 118x.

The side stops 119 and leveling up pins 120 which correspond to the stops 54 and pins 55 50 above described, are adjustably supported by the spaced rails 121 which are rigidly secured by the screws 122 to the opposite edges of the head 112. Between the spaced rails 121 is slidably supported a block 123 similar to the block 67, and to the opposite faces of this block are secured the block supporting strips 124 and 125, the latter having a dove-tail construction to slidably support the slide 126 upon which the heel engaging stops 119 are mounted as in the slide 70 above described. 60 These stops are moved towards and from the heel by the right and left screw 127 having the head 128. The slide 126 is locked against sliding movement in the direction of its length by the locking screw 129.

In this modified construction the means for supporting the stops 119 and pins 120 may be adjusted towards and from the lathe head 112 to accommodate different size lasts, and the graduations 130 are provided to facilitate this adjustment. The locking screw 131 is provided for locking the block 123 in the desired position of adjustment along the rails 121. The tread engaging pins 120 are adjusted by the nut 132 similar to the pins 55.

In employing this modified construction of

Figs. 12, 13 and 14 a model last L is placed in the chuck so that its axis of rotation is lined up with the lathe axis and while the last is retained in this position the abutment plate 115, stops 119 and pins 120 are moved into engagement with the last. The model last may then be removed and a last to be reformed of the same size inserted in the chuck, whereupon it will be properly centered in one plane by operating the screw head 128 to bring the stops 119 against its opposite faces. 10 This last is centered in a second plane by the engagement of the tread of the heel with plate 115 and pins 120, and it is held firmly thereagainst by the clamping screw 133. This screw is threaded in an extension 134 secured to the head 112 15 and is rotated by the hand wheel 135. The lower end of this screw has the pivoted head 136 which engages the top of the last.

The last positioning and clamping means just described will support the last to be reformed 20 with its axis position similar to that of the model last used in setting up the clamping parts, so that the toe engaging centre 137 of the lathe may be forced against the toe block to support this end of the last during the turning operation under the 25 action of the cutter 138. In this manner the last to be reformed may be quickly and accurately positioned upon a lasting lathe ready for the turning operation without providing the borings in the heel and side of the last as contemplated by 30 the construction shown in Figs. 1 to 11 hereof.

Having thus fully described my invention, I claim and desire to secure by Letters Patent of the United States:

1. The method of reforming lasts which comprises fixedly supporting a model last in a determinate position and while thus supported forming longitudinal borings in the heel and toe portions thereof which define the axis for said last, fixing the heel portion only of each of the other lasts 40 in the same determinate position as the heel portion of said model last was fixed and forming longitudinal and transverse borings in said heel portion which define an axis therein like the axis of said model last, replacing with a fore block 45 the fore part of each of the lasts to be reformed, supporting in a determinate axial position each of the lasts to be reformed by positioning elements engaging the borings in the heel portion thereof and while thus supported forming a positioning 50 centre in the fore end of its fore block, setting up the model last and in turn each of the lasts to be reformed with supporting elements engaging certain of the borings therein whereby the lasts will be arranged preparatory to cutting in determinate axial positions, and cutting the lasts to be reformed to conform to the model last.

2. In the method of reforming lasts the steps which comprise fixing the heel portion only of each of the lasts to be reformed in the same determinate position as the heel portion of a model last was fixed and forming longitudinal and transverse borings in said heel portion which define an axis therein like the axis of said model last, replacing with a fore block the fore part of each of the 65 lasts to be reformed, and supporting in a determinate axial position each of the lasts to be reformed by positioning elements engaging the borings in the heel portion thereof and while thus supported forming a positioning centre in the fore 70 end of its fore block.

3. The method of reforming hinged lasts in conformity with a model last, which consists in supporting each last to be reformed entirely from its heel part by placing the heel part of the last 75

in a centering device that has been previously adjusted to support the last on an axis corresponding to the axis of the model last and exerting pressure on the opposite sides of the heel part 5 to centre the last in a longitudinal plane passing vertically through the heel, while the last is thus supported forming borings longitudinally and transversely of the heel part so that they bear a definite predetermined relation to the axis upon 10 which the last is to be reformed, replacing with a fore block the fore part of the last, then supporting the last from said borings and while thus supported forming a centre bore in the toe of the last, turning the last about said centre bore 15 and cutting the last to be reformed to conform to the model last.

4. The method of reforming lasts in conformity with a model last, which includes the steps of fixedly positioning the heel part only of each 20 of the lasts to be reformed by placing each of these lasts in a centering device that has been previously adjusted to support the heel part of the last on an axis corresponding to the axis of the model last and exerting pressure on the 25 opposite sides of the last to centre it in a longitudinal plane passing through its tread, while the last is thus supported forming longitudinal and transverse borings therein to bear a definite predetermined relation to the axis upon which the 30 last is to be reformed, supporting the last from said borings and while the last is thus supported forming a centre bore in the toe thereof.

5. The method of reforming lasts in conformity with a model last, which includes the steps of 35 supporting each last to be reformed by engaging the last at each side of its rounded heel end to centre the heel end of the last, forcing the tread of the last against a support to position the last in one plane, exerting pressure upon an intermediate portion of the last at its opposite sides to position it in a second plane at right angles to the first, while the last is thus supported forming borings therein so that they occupy a predetermined relation to the axis upon which the last 40 is to be reformed, supporting the last from these borings and while the last is thus supported forming a centre bore in the toe thereof.

6. The method of reforming lasts in conformity with a model last which includes the steps of 50 fixedly supporting a model last in a determinate position for defining the axis of said last, replacing with a fore block the fore part of each of the lasts to be reformed, fixing the heel portion only of each of the lasts to be reformed fitted 55 with a new fore block as aforesaid in the same determinate position as the heel portion of said model last was fixed whereby it will have the same axis as said model last and while thus fixed forming a positioning centre in the fore end of 60 its fore block.

7. Mechanism for locating a turning axis in a last comprising in combination V-blocks or the like for receiving and longitudinally centering the heel and toe of the last for defining the position 65 thereof in a vertical plane, means for defining the position of the last in a plane at substantially right angles to the first named plane, means for fixedly retaining the last in said defined positions, and means for forming borings in the heel and 70 side of said last while fixedly retained as aforesaid.

8. Mechanism for locating a turning axis in a last comprising in combination V-blocks or the like for receiving and longitudinally centering 75 the heel and toe of the last for defining the

position thereof in a vertical plane and including side stops movable into a defined position of engagement with the sides of the heel portion of the last, means for defining the position of the last in a plane at substantially right angles to the first named plane, means for fixedly retaining the last in said defined positions, means for making borings in the end and side of the heel portion of said last while fixedly retained as aforesaid, side stops movable into a defined position of engagement with the sides of the heel portion of the last, and means whereby said side stops may be simultaneously adjusted in an equal amount toward or away from each other with relation to their said defined position. 15

9. Mechanism for locating a turning axis for a last comprising means for making borings at the end of the heel portion of the last and in the side of said heel portion, and means for fixedly securing the last to receive said borings including a V-block for receiving and longitudinally centering said heel portion, and side stops movable into a defined position of engagement with the sides of said heel portion when said heel portion is centered by the V-block as aforesaid, and 25 means whereby said stops may be simultaneously adjusted in equal amount towards and away from each other with relation to their said defined position.

10. Mechanism for locating a turning axis for 30 a last comprising means for making borings at the end of the heel portion of the last and in the side of said heel portion, and means for fixedly securing the last to receive said borings including a V-block for receiving and longitudinally 35 centering said heel portion, tread engaging means, side stops movable into a determinate position of engagement with the side of said heel portion when said heel portion is centered by said V-block as aforesaid and which side stops are simultaneously adjustable in an equal amount towards or away from their said defined position, and means for forcibly holding the last against said tread engaging means.

11. Mechanism for locating borings in each 45 last of a series of lasts to be reformed so that these borings will occupy a predetermined relation to the axis upon which the last is to be reformed, comprising in combination, a support having a seat for the tread of the heel and a 50 V-block or the like for centering the heel end of the last, tread engaging means positioned to co-operate with said seat to centre the last in one longitudinal plane, centering means adapted to co-operate with said V-block to centre the 55 last in a second longitudinal plane, and means for forming positioning borings longitudinally and transversely of the last while thus supported.

12. Mechanism for locating borings in each 60 last of a series of lasts to be reformed so that these borings will occupy a predetermined relation to the axis upon which the last is to be reformed, comprising in combination, a support having a seat for the tread of the heel and a 65 V-block or the like for centering the heel end of the last, tread engaging means positioned to co-operate with said seat to centre the last in one longitudinal plane, means for holding the last against said tread engaging means and seat 70 with the tread of the last up, means adapted to co-operate with said V-block to centre the last in a second longitudinal plane, and means for forming borings in the last while thus supported.

13. Mechanism for locating borings in a last so 75

that they occupy a predetermined relation to the axis upon which the last is to be reformed, comprising in combination, a support having a seat for the tread of the heel and a V-block or 5 the like for centering the heel end of the last, tread engaging means positioned to co-operate with said seat to centre the last in one longitudinal plane, side stops adapted to co-operate with said V-block to centre the last in a second 10 longitudinal plane, and means for forming positioning borings in a side and end of the last while thus supported.

14. Mechanism for locating borings in a last so that they occupy a predetermined relation to 15 the axis upon which the last is to be reformed, comprising in combination, a support having a seat for the tread of the heel, tread engaging means positioned to co-operate with said seat to centre the last in one longitudinal plane, side 20 stops adapted to engage the opposite sides of the last to centre the last in a second longitudinal plane, a slide for supporting said stops and mounted for lateral movement to position the stops to receive either a right or a left last, means 25 for adjustably supporting the stops on said slide, and means for forming positioning borings in the last while thus supported.

15. Mechanism for locating borings in a last so that they occupy a predetermined relation to the 30 axis upon which the last is to be reformed, comprising in combination, a heel engaging V-block having a seat for the tread of the heel of a last, tread engaging means positioned to co-operate with said seat to centre the last in one longitudinal plane, side stops adapted to co-operate with said V-block to centre the last in a second longitudinal plane, means for forming positioning bores in the last while thus supported, 35

and means for supporting said V-block for adjustment lengthwise of the machine to accommodate different size lasts.

16. Mechanism for forming borings in a last so that they occupy a predetermined relation to the axis upon which the last is to be reformed, comprising in combination, a heel engaging V-block having a seat for the tread of the heel of a last, tread engaging means positioned to co-operate with said seat to centre the last in one 10 longitudinal plane, last engaging means adapted to co-operate with said V-block to centre the last in a second longitudinal plane, means for forming positioning bores in the last while thus supported, and means for supporting said V-block 15 for adjustment along an inclined path to cause its seat to recede from a horizontal plane as the V-block is moved in a direction to receive a larger last.

17. Mechanism for locating borings in a last 20 so that they occupy a predetermined relation to the axis upon which the last is to be reformed, comprising in combination, a support having a seat for the tread of the heel, tread engaging means positioned to co-operate with said seat 25 to centre the last in one longitudinal plane, side stops adapted to engage the opposite sides of the last to centre the last in a second longitudinal plane, a slide having said stops adjustable there-upon and mounted for lateral movement to position the stops to receive either a right or a left last, means for forming positioning borings in the last while thus supported, and a pivoted stop movable from one side to the other of a fixed central support to limit the movement of 30 the slide in one direction to an amount equal to its movement in the opposite direction. 35

JEREMIAH FITZPATRICK.
